COLLOIDAL DENSITOMETER

Gerson L. Ram, Passaic, and Robert G. Salomon, Bloomfield, N.J., assignors to Board of Trustees of Schools for Industrial Education of Newark, New Jersey, Administering Newark College of Engineering, Newark, N.J., a public corporation of New Jersey

Filed Jan. 18, 1960, Ser. No. 3,015
7 Claims. (Cl. 88—14)

This invention relates to a device for measurement and precise recording of the degrees of opacity to the passage of light from a source of constant intensity through a scanned column of liquid, usually containing the matter being investigated as a suspension therein, so that the user may classify such matter and evaluate the nature, quality and characteristics thereof. The invention will enable such classification and evaluation to be attained for the first time in some cases and to a degree of accuracy and refinement in other cases not heretofore possible. For example, it will enable such matter as proteins, dissolved or suspended in said liquid, to be readily so evaluated and classified.

Probably the most unexplored, confused and chaotic field of chemistry is that of the proteins. At the turn of the century, Abderhalden estimated that, on the basis of the amino acids known at his time, possible combinations of these acids would give 5½ pentillion different protein compounds. It may be assumed on this basis alone, that the large number of compounds involved would make protein differentiations extremely difficult. In addition to the large number of proteins, another difficulty stems from the fact that proteins are all very similar in chemical composition; for example, they all are compounds of hydrogen, oxygen and carbon containing about 15% nitrogen. Consequently, the classical methods of analytical chemistry have given no simple system for the recognition of individual proteins. Such recognition of individual proteins is very important; in some cases being the difference between life and death, since very closely related proteins such as albumens, coming from one animal species, are completely rejected when transferred into a second animal species. Yet, these differences cannot be determined or picked up by any simple chemical test, and at the present time, only the trial and error biological tests, such as in typing blood for transfusions, are generally known.

Another peculiarity which makes the differentiation of proteins a great problem is the capability of these substances for denaturation radically by such things as heat, light, radiation energy, or chemical agents. Again, this is a vital difference, representing the difference between life and death or health and disease.

Another factor involving the difficulties in working with proteins is the fact that these substances are capable of being used as food materials by various microorganisms and, consequently, will undergo microbial decomposition unless protected in a manner which does not denature the protein.

The present invention embodies the utilization of objective methods for the recognition of proteins. Ultimately, all chemical recognition problems are reducible to objective physical measurements. It makes possible the physical measurements of individual proteins suspended as colloids in a suitable liquid medium and protected from bacterial action, as by being held at a low temperature (approximately zero degrees centigrade). The physical measurements made by an instrument embodying this invention involve the tracking of the movements of protein colloids in a high voltage, extremely low-amperage direct current electrical field. These protein colloids are suspended in a cold water solution of

2

non-ionic buffering character, desirably having a pH of about 8.6. The movement of the particles in the electrical field on a time basis is established by measuring light transmission across a column of liquid containing the protein under examination as a colloidal suspension, the entire length of the column of liquid being scanned by a moving light source. The small impediment offered by the particles to the transmission of light is greatly amplified electronically by a photosensitive electron tube amplifier mechanism.

Heretofore, optical systems of magnification were used to record changes in index of refraction. In the present invention electronic principles are used to measure impedance to direct transmission. Ultimately, several large categories of protein differentiation should emerge as experience in physical measurement of the qualities described herein produces sufficient data.

The disclosure herein of an illustrative use of the invention, for translation of the degree of opacity of matter in a column to passage of light from a source of constant intensity therethrough into visible indicia, is illustrative of a large number of other uses of the invention which will become apparent to those skilled in the art.

The drawings, illustrating procedures and devices useful in carrying out the invention, and the description below, are exemplary only of the invention, which shall be deemed to cover all other devices and procedures coming within the scope and purview of the appended claims.

30 In the drawings:

FIGURE 1 is a partly schematic side elevational view of apparatus embodying the invention,

FIGURE 2 is a fragmentary end elevational view thereof, taken at line 2—2 of FIGURE 1, in the direction of the arrows,

FIGURE 3 is a fragmentary top plan view, with parts in horizontal section, taken at line 3—3 of FIGURE 2,

FIGURE 4 is a fragmentary elevational view of the cassette and its housing frame forming part of the apparatus of the preceding figures and embodying the invention, and

FIGURE 5 is a horizontal sectional view of the cassette and its frame on the line 5—5 of FIGURE 4.

Pursuant to the invention, a transparent or translucent container or cassette 10 (FIGURES 4 and 5) formed, for example, of a solid block of plastic or glass, is provided, and a pair of parallel chambers 11, 12 are cut therein and interconnected at their lower ends by a cross-over passage or port 13 with a filling pipe 24, connecting therewith through a passage 23. At the upper end, passages, such as 14, 15 and 16, are formed connected through pipes or tubes 17 to the vessels 18 at the sides of the chambered block. Thus, the upper end of each chamber is connected to the adjacent vessel. The vessels 18 are interconnected thereabove by a bridge pipe 25 so that overflow from one vessel will pass to the other. The chambers 11 and 12 may be vented, as by the pipes 19, 20 connected thereto by the passages 14. Cassette 10 may be suspended in a surrounding housing frame 22 as by a vertically adjustable rod 21. The vessels 18 are corked or otherwise closed as at 26, electrodes 27, 28 being projected into the vessels 18 and connected externally thereof with a power source (not shown) for imposing a unidirectional difference in potential between said electrodes. The flow of current may be from electrode 27, through the liquid in tube 17 at left, passage 14, the column of liquid in chamber 11, passage 13, the column of liquid in chamber 12, passage 14, and tube 17 at right to electrode 28.

70 The housing frame 22 is sealed watertight as by and between a pair of light-permeable plates 29, 29' (FIGURES 1 and 5) the latter being also sealed to light hoods

39, 30'. Light rays pass from the source 38 through lens 39 from whence they emerge as a thin beam of light 40 which may, if desired, be trimmed to a still smaller dimension, say about $\frac{1}{16}$ " in diameter, by passage through an aperture of corresponding size in a diaphragm (not shown). Such a beam 40 passes through the cassette 10 from the light source 38. The source 38 is movable vertically on the externally threaded shafts 42 (FIGURE 2) journaled in the platform 43 for free rotation about vertical axes, said shafts also passing freely through bearings 44 on the front wall 37 of the tank (FIGURE 1). Bevel gears 45 (FIGURES 1 and 2) are fixed to the upper ends of the vertical shafts 42 and mesh with bevel gears 46 of a shaft 47, which may be supported in bearings 52. A pinion 49 fixed on shaft 47, meshes with pinion 50 of a second horizontal and drive shaft 51, passing freely through support bearings 52.

The vertical shafts 42 may be rotated manually as by the hand wheel 63 (FIGURE 2) keyed to shaft 51 or by the pulley 55 keyed to shaft 51 and driven by a belt or other means 56 actuated by a motor (not shown). A hand crank 53 may be keyed to one of the vertical shafts 42 so that the shafts may thus be manually or automatically actuated as desired for a purpose now to be explained. The light source 38 may be secured to blocks 41 by a beam 60 (FIGURE 2) having slots 63 for the adjustable reception of threaded posts 64 fixed to bosses outstanding from the blocks 41 which are threaded on the shafts 42. Wing nuts 65 threaded on the posts 64, may be used to tighten the beam 60 at the desired position horizontally on the blocks 41.

Thus the light source 38 may be shifted to selective alignment with one of the chambers 11 and 12, or for re-alignment from one to the other rapidly and accurately as desired. The blocks 41 are thus mounted for movement vertically on rotation of the shafts 42 to correspondingly move the light source 38 to act as a scanning device. The beam 60 may be provided with markings (not shown) for registering with markings (not shown) on the blocks 41, to precisely align the light source 38 with one of the chambers 11 and 12, as desired. The light source 38 should be constant in output and of sufficient intensity to generate a light beam 40 (FIGURES 1 and 3) of strength or intensity sufficient for the purposes herein mentioned. A motor-driven carriage is thus provided (beam 60, blocks 41, shafts 42, 47, 51 and belt 56) so that the light source 38 may be moved at a constant or desired rate of speed vertically in line with a liquid in the selected one of the chambers 11 and 12 for test or measurement of the degree of opacity of said liquid to passage of the light beam 40 therethrough.

The housing frame 22 and associated parts are desirably immersed in a liquid in a tank 37, preferably refrigerated to about zero degrees C. To that end, a refrigerator or refrigerating unit 66 (FIGURE 1) may be provided with refrigeration coils, fragments of which are shown schematically at 67, extended and disposed within the tank 34. The refrigeration prevents overheating of the solutions in the chambers 11, 12, by the electrical current flowing therethrough, inhibits the growth of bacteria, and eliminates thermal currents which might upset boundary demarcations in the liquid or suspension in the chambers.

The power may be from any suitable current supply source to which electrodes 27, 28, are connected. A high voltage unidirectional source, not necessarily high powered, because only a small current flows, is desired, to produce a potential difference inducing electrophoretic operation. The apparatus of the invention electronically magnifies and measures the differences in degree of optical density caused by the differences in colloidal segregation along a considerable length of non-uniform solutions in one of the chambers 11 and 12, as the scanning device 38 tracks the length of the liquid. The particles measured are colloidal, the apparatus being used to measure the optical density of the materials which have no appreciable

scattering effect and which have no significant resistance to the passage of light other than that the refractive index is slightly changed.

In operation, the colloidal matter, suspended in the test samples disposed in the chambers 11 and 12 of the cassette 10, is electrophoretically caused to migrate across a boundary formed with a buffering liquid, while scanned by the light beam 40. Said beam 40 has its rays directed substantially parallel to one another by the lens 39. Its source 38 is driven by a turning of the threaded shafts 42. After passing through the cassette, the light beam 40 is picked up by a photoelectric cell 35 and the output intensity permanently recorded as a graph 59 where the readings can be calibrated and quantitatively compared with a solution of known characteristics. The cell 35 has a sensitive area large enough to receive the output beam of light at any position of its range from one chamber 11 to the other chamber 12 and over its entire range of vertical movement.

In using the apparatus of the invention, the buffer (such as a cold water solution of a non-ionic character, pH 8.6) is first poured through funnel 67 into the chambers 11 and 12 and then the test solution or suspension (which may be a protein) poured in, following the buffer and moving up so that separation of the buffer and test solution occurs about halfway up the chambers 11 and 12. The bath in tank 34 is kept at constant refrigeration temperature and the apparatus is set up to track chamber 11 or chamber 12, i.e., to vertically move the light source at a constant speed in line with said chamber. If it is found that the migration of the colloidal suspension in the chamber so being tracked is in a reverse direction to the direction of vertical movement of the light source, the latter is shifted to the other chamber, to track the latter (wherein the migration of the colloidal suspension will be reversed to that of the first tried chamber) and thus will be suitable for the direction of tracking of the light source. The use of two chambers for the matter being tested is desirable as it is not always possible to predict the direction of migration or propagation. The possibility of the boundary or interface moving out of the field of the light beam is thus obviated. The graph formed on the record of recorder 59 which is thus obtained, is calibrated against a graph of a standardized liquid.

The degree to which the beam 40 of light is intercepted by the chamber 11 (or 12) and variations along the length of the chamber will correspondingly modulate the light beam. It will be noted from the disclosure herein that where a chart or graph is used to record the intensity of the residue of the light beam 40 after passage through the chamber 11 or 12 and on to the photoelectric cell 35 (any other light-current converter suitable for the use described may be used in lieu of the cell 35) the output current so generated passes through cable 36 in a water-tight tube 31 and through an amplifier 32 of desired characteristics and actuates a stylus 58 to make a record on a chart or record sheet of recorder 59. Any other recorder may be used in lieu of recorder 59. By thus recording the rate of migration, the material of which samples have been placed in the chambers 11 and 12 may be precisely evaluated and classified.

Having now described the invention in detail in accordance with the requirements of the patent statutes, those skilled in this art will have no difficulty in making changes and modifications in the individual parts or their relative assembly in order to meet specific requirements or conditions. Such changes or modifications may be made without departing from the scope and spirit of the invention, as set forth in the following claims.

We claim:

1. In a densitometer device for tracking the movement of particles suspended in a liquid column at a boundary with a buffer liquid, a light permeable container for said liquid column, means for impressing a difference in electrical potential across said boundary, a light source mov-

ably mounted relative to one face of the container for directing a beam of light through the liquid in the container, said light source being movable along the entire length of the container, a device beyond the other face of the container and sensitive to the light beam so passed through the column, means for effecting relative movement between the light source and the container at a constant rate of speed for scanning the full length of the contained liquid by said beam, and means for recording the intensity of the beam after passing through said column as a measure of the degree of opacity of said column throughout the entire length thereof to the passage of said beam as registered by said light sensitive device.

2. In a densitometer device as set forth in claim 1, a light-permeable chamber in said light-permeable container for so suspending said particles in the liquid column, a supply pipe for filling said chamber, and air venting means for said chamber.

3. In a densitometer device as set forth in claim 1, wherein the means for impressing a difference in potential includes a vessel at each side of the container, an electrode in each vessel, and liquid passageways from said vessels to opposite ends of said column.

4. In a densitometer device as set forth in claim 1, a second liquid column for alternative use disposed to one side of the first-mentioned liquid column, and means connecting said first and second liquid columns to allow liquid to flow therebetween.

5. In a densitometer device as set forth in claim 4, means for laterally moving said light source to remove the beam of light from one liquid column and selectively direct it to the other column.

6. In a densitometer device as set forth in claim 1,

10

wherein the container consists of a block of translucent material, a pair of chambers formed therein and parallel to one another, a passage in said material connecting the lower ends of said chambers, a filling pipe leading to said passage, a vessel disposed at each side of said block, and a passage in said block connecting the upper end of each chamber to the adjacent vessel.

7. In a densitometer device as set forth in claim 1, wherein there is a housing frame surrounding and sealed watertight, to enclose said container, by means of light-permeable plates, one in front and one behind said container, and means for adjustably suspending said container in said frame.
